DRAWER

Earl M. Stevens, Chicago, Ill.

Application July 11, 1935, Serial No. 30,797

10 Claims. (Cl. 235—22)

The invention relates to drawers of the type used as repository for valuables or money, and particularly refers to cash drawers used in cash registers.

5 It is an object of the invention to provide a drawer which may be opened and closed at will and which may be closed from a distance upon an emergency.

A further object aims at providing a safety 10 device for a drawer which device ordinarily does not interfere with the unrestricted opening or closing of the drawer but operates to automatically close the drawer from any position thereof when desired by remote controlled means.

15 A still further object aims at providing a safety device for a drawer which is completely detached from and ordinarily does not engage said drawer, but which device enters into engagement with said drawer at any position thereof upon actuation of a distant control and automatically closes the drawer to prevent burglary.

A still further object includes the provision of a safety device which, when the drawer is closed, prevents upon an emergency opening of the 25 drawer.

It is also an object of the invention to provide a cash register with a safety cash drawer so that from a distance the open drawer may be closed if an unauthorized person attempts to 30 rifle the same.

A further object aims at providing a safety device which includes an arm underneath the drawer and normally detached therefrom, but which arm is adapted to enter into engagement 35 with said drawer upon the device being brought into action.

Other and equally important objects will become more apparent from a perusal of the invention which comprises the means described in the 40 following specification, particularly pointed out in the claims forming a part thereof, and illustrated in the accompanying drawings, in which

Fig. 1 is an elevational view of a cash register to whose cash drawer the invention is applied.

45 Fig. 2 is a section on the line 2—2 of Fig. 1.

Fig. 3 is a section on the line 3—3 of Fig. 1.

Fig. 4 is a section on the line 4—4 of Fig. 3.

Fig. 5 is a section on the line 5—5 of Fig. 3.

Fig. 6 is a section on the line 6—6 of Fig. 5.

50 Fig. 7 is a section through a modified form of cash drawer.

Fig. 8 is a section on the line 8—8 of Fig. 7.

Fig. 9 is an enlarged fragmentary section through the right lower end of the parts shown 55 in Fig. 8.

Fig. 10 is a section on the line 10—10 of Fig. 9.

Fig. 11 is a wiring diagram used in connection with the safety device for the drawer.

Referring to the figures, the casing 10 may be of any suitable shape and is herein rectangular 5 in cross section. It is adapted to receive the usual cash register 11 which may be secured thereto, for example, by bolts 12. The casing is formed with an opening 13 for the cash drawer 14. An additional opening 15 is provided at the 10 rear of the casing which is closed by any suitable door 16, formed with locking members 17 and also may include one or more locks 18.

Positioned within the casing is a similarly 15 formed inner housing 19 which may be insulated from the outer casing by any suitable electrical insulation 20. The compartment of the inner housing may be divided by a wall 21 to provide a chamber 22 for the mechanism later described and a chamber 23 for the cash drawer 14. The 20 drawer may be of the conventional type with the usual cash compartments and may be supported upon a rail 24 by a roller 25. Additional angular members 26 fastened on either side of the drawer are supported and guided by rollers 27 secured to 25 the housing 19. Fastened to the rear wall of the cash drawer is a bracket 28 apertured as at 29 to receive a locking pin 30, operable by any suitable mechanism associated with the cash register 11. The mechanism for actuating the pin 30 is not 30 illustrated since it forms no part of the present invention. The cash drawer 14 preferably is provided with springs 31 to open the drawer when the pin 30 is withdrawn from the slot 29. The springs 31 may be received in cup-shaped members 32 secured to the wall 21.

Note that the front wall 33 of the cash drawer 14 is insulated by an insulating plate 34 from the cash drawer, the purpose of which will later appear.

40 In housing 19 is a horizontal partition 40 which at its ends is bent down to form vertical flanges 41 so as to maintain the partition space above the bottom. The partition has a slot 42 for the reception of a lever 43 which is pivoted in a pendant bearing 44 secured to the underside of the partition. The lever at one end carries a pin 45 adapted to engage a pawl 46 which is pivotally mounted upon an arm 47. The arm 47 is pivoted as at 48 upon the partition 40 and is normally 45 held in the dotted line position of Fig. 3 by means of a spring 49 secured at one end to a medial part of the said arm and at the other end to the vertical partition 21.

50 A stop 50 secured to the partition 40 prevents 55

the arm 47 to move inwardly past a predetermined position. The free end of the lever 43 extends through an aperture 51 of the sliding member 52 which is reciprocatingly mounted in a guiding member 54. The sliding member 52 is provided with a central slot 55 into which extends a plunger 56, having a cam portion 57 at its free end to actuate said sliding member. The plunger 56 is secured to an insulating disk 58 carried by solenoid plungers 59, which are mounted in solenoids 60. The solenoid plungers 59 are normally maintained in outward position by springs 61 arranged between the solenoids and the heads of the plungers 59. The slide 52 is normally maintained in lowermost position by a spring 62 bearing on the adjacent end of lever 43 and entering a depression in wall 21 and the pressure exerted on said lever operates to maintain the slide in the lowermost position. The pin 45 of the lever 43 projects above the partition 40 and serves to engage a lug 64 on the pawl 46 to retract the free end of the pawl from the rack 65 secured to the underside of the drawer 14, so as not to interfere with or restrict the reciprocating movements of the drawer. A spring 66 bearing on the lug 64 and entering a depression in the arm 47, turns the pawl into the dotted line position of Figure 5, so that the latter engages the teeth of the rack 65. The partition 40 is provided with the additional slot 67 for the reception of a lever 68 pivoted in a pendant bearing 69 secured to the underside of the partition 40. The lever is formed at one end with a cam 70, whereas the other end of said lever engages with a lock plunger 71 reciprocatingly fitted in a lock housing 72, containing a lock 73, which is formed with a tooth 74 entering a recess 75 of a horizontal bar 76, which acts on the plunger 71 to keep it in lowermost position. The tooth 74 bears on the flat part of slide 76 at the right of notch 75, when the slide is in its left hand position (Fig. 6). When slide 76 is moved to the right by the plunger 71 the tooth 74 may enter the notch 75 through a turning movement applied to lock barrel 73 by a spring 73a. The lock bar 76 is normally held in position illustrated in Fig. 6 by means of a spring 77 secured at one end to the bar and at the other end to the housing 72 as at 78.

The partition 21 is provided with an aperture 80 through which extends the leg of a locking lever 81, which is pivotally mounted as at 82 on a supporting block 83 provided on the drawer 14. A spring 84 secured to the block 83 bears on the locking lever 81 to maintain the lever in normal position as indicated in Fig. 3. From the foregoing it is clear that when the arm 47 is caused to move inwardly the lever 68 is depressed and the plunger 71 raised. The beveled edge thereof shifts the bar 76 to be held in closing position by the tooth 74 of the lock 73.

When the drawer 14 under emergency operation reaches closing position, its lever 81 snaps over the slide 76 and holds the drawer in locked position until such time as the lock 73 is opened by a key.

Secured to the casing 10 and adjacent to the top thereof is a lock 86 provided with a stem 87 to which is secured a cam 88 adapted to close a switch 90 (Fig. 4) secured to the housing 19, the purpose of which will be later described. An additional switch 92 (Fig. 5) is secured to the housing at the top thereof, which switch is adapted to be actuated by a pivoted lever 93 arranged

in the cash register and actuated by keys 94 of the cash register.

In Figure 11, a diagram is shown of the electrical circuits necessary for the operation of the drawer. 95 and 96 designate the main leads to which is connected the primary of a transformer 97. The secondary of said transformer is grounded at one end as at 98 while the other end is connected through a switch 99 to a multiple switch 100 normally held in open position and whose one terminal 101 is grounded as at 102 through the wall of the casing 10. A multiple switch 103 is provided adjacent to switch 100 and adapted to be actuated simultaneously by an arm 106 held in open position by a relay arm 107 controlled by a relay 108 and by a spring 109.

A line 110 leads from the positive power line 96 to the switch 104, which, in the position illustrated in Fig. 11, is in electrical contact with the switch member 105 from which a line 111 extends to the solenoids 60 which by means of the line 112 completes the circuit to the negative power line 95. The switch member 103 of the multiple switch is in electrical circuit with an alarm 113, and is connected by a wire 114 through one side of a relay 115, which may be located elsewhere, for example, in a police station. A line 116 originating at the relay 115 completes the electrical circuits to the line 112 and negative main 95. The relay 115 is adapted when energized to close a switch 117 which controls an alarm 118, preferably located in the vicinity of the relay 115.

In electrical connection with the power line 96 by means of a line 120 are a plurality of switches 121 which may be located at various points of the store, in which my invention is located, and which serve to energize the relay 108 previously described.

In operation: The drawer is first taken out and the arm 47 is swung into the position shown in Fig. 3, it being understood that the multiple switch 100 actuated by the relay 108 is set in the position shown in Fig. 3 to energize the solenoid 60. In that position the arm 47 is held by the lever 43 which engages with the pin 45 the lug 64 of pawl 46 so that the arm 47 is held in functional position but at the same time is disengaged from the drawer, so as not to interfere with the unrestricted opening or closing thereof. Now if one of the switches 121 is closed or switch 92 is closed by the cash register keys, provided switch 90 is in dotted line (closed position) then the relay 108 is energized which trips arm 106 causing the circuit through solenoid 60 to break and closes circuit through the alarm and charges the inner casing with high voltage. A switch 152 is provided at the rear of the casing, as shown in Fig. 7, which is held in open position by a lug 153 secured to the drawer 14 when the drawer is in closed position. As soon as the drawer is opened, the switch 152 closes. If the switch 90 is in dotted line position (Fig. 11) forcible opening of the drawer 14 closes the switch 152 and energizes the relay 108 which in turn closes the switches 100 and 103 and opens the switch 105 whereby the solenoid 60 is de-energized, permitting the plunger 56 to release the sliding member 52 cooperating with the lever 43 so that the arm 47 is released and the drawer locked against opening.

The modified form, shown in Figs. 7 to 10, in substance is of a similar construction as the first embodiment described. However, the means for closing the cash drawer 14 are as follows: Mounted preferably centrally of the cash box 10 is a tube 125, which is mounted upon standards 75

126 and 127, illustrated in Figs. 7, 8 and 9. The tube 125 is provided with slots 128 (Fig. 10) adapted to receive a connecting portion 129 of a slidable sleeve 130, which is slidably mounted upon the tube 125. The sleeve 130 is formed with lugs 131 to which are secured the ends of springs 132, the opposite ends of which are fastened to the casing as at 133. The portion 129 of the sleeve 130 is provided with a downwardly projecting lug 134 adopted to engage a plunger bar 135 projecting through an aperture 136 in the tube 125, as shown in detail in Fig. 9. The plunger bar 135, slidably mounted in guiding members 136, is normally held in position, illustrated in Fig. 9 by means of a spring 137 in order to lock the member 136. The lock bar 135 is provided with a slot 138 to receive the cam portion 140 of a plunger 141, similar in construction as the plunger 61, previously described. The plungers 141 are mounted in the usual manner in the solenoid 142. Adjacent to the left hand side of the rail 125, as viewed in Figs. 7 and 8, is mounted a latch member 143 projecting through a slot 144 in the rail 125. The latch member 143 is secured to a spring member 145 formed with a terminal portion 146, adapted to be engaged by a cam 147 carried by the stem 148 of a lock 149. It will be understood that the cam 147 serves to depress the spring 145 to permit the cam latch 143 to be drawn inwardly into the tube 125. The latch member 143 is adapted to engage the bridge 150 formed on the sleeve 130, previously described. The bridge 150 further serves to engage an angle member 151 on the cash drawer 14. Attention is called to the fact that the latch 143 does not become effective until the bridge 150 reaches the dotted line position shown in Figure 7.

The embodiment shown is predicated on the provision that upon the opening of the circuit the means are set in operation in order to automatically close the drawer. It is, of course, within the purview of the invention to obtain the actuation of the closing means by closing a circuit.

While the drawings show preferred embodiments of the invention, numerous changes and alterations may be made without departing from the spirit of the invention. I, therefore, do not want to be limited to the details of construction or arrangement of parts as shown, but claim my invention as broadly as the state of the art permits.

I claim:

1. In combination with a sliding drawer, a spring tensioned drawer closing member, means for releasably retaining said member in retracted position to permit normal actuation of the drawer, and means responsive to release of said member and movable transversely to the path of the drawer for interconnecting the drawer and said member to effect movement of the drawer to innermost position.

2. In combination with a sliding drawer, a spring tensioned drawer closing member, means for releasably retaining said member in retracted position to permit normal actuation of the drawer, and means responsive to release of said member for interconnecting the drawer and said member in different positions of the drawer.

3. In combination with a sliding drawer, a spring tensioned drawer closing member, means for releasably retaining said member in retracted

position, electrically operated means for releasing said member, and means responsive to release of said member and movable transversely to the path of the drawer for interconnecting the drawer and said member to effect movement of the drawer to innermost position.

4. In combination with a sliding drawer, a movable spring tensioned drawer closing member, means for releasably retaining said member in retracted position, a normally ineffective latch for holding the drawer closed, means for conditioning the latch by closing movement of said member for effective operation, and means responsive to release of said member for interconnecting the drawer and said member in different positions of the drawer.

5. In combination with a sliding drawer, a spring tensioned drawer closing member, means for releasably retaining said member in retracted position, means responsive to release of said member for interconnecting the drawer and said member to effect closing of the drawer, and means for giving an alarm upon forcible movement of the drawer from closed position subsequent to operation of said member.

6. In combination with a sliding drawer, a spring tensioned drawer closing member, means for releasably retaining said member in retracted position, means responsive to release of said member for interconnecting the drawer and said member to effect closing of the drawer, and means for charging said drawer with high voltage upon forcible movement of the drawer from closed position subsequent to operation of said member.

7. In combination with a sliding drawer, a spring tensioned drawer closing member, means for releasably retaining said member in retracted position, and means responsive to release of said member and movable transversely to the path of the drawer for interconnecting the drawer and said member to effect closing of the drawer, said interconnecting means remaining in interlocking engagement with the drawer after release of said member.

8. In combination with a sliding drawer, a spring tensioned arm adapted to close the drawer, a spring pressed pawl mounted on said arm for engagement with the drawer, means for releasably retaining said pawl and said arm in retracted positions, and means for withdrawing said retaining means to permit movement of said pawl to engage the drawer and movement of said arm to effect closing movement of the drawer.

9. In combination with a sliding drawer, a spring tensioned drawer closing member, means for releasably retaining said member in retracted position, and means responsive to release of said member for interconnecting the drawer and said member in different positions of the drawer, and for maintaining the interconnection after closure of the drawer by said member.

10. In combination with a sliding drawer, means including a spring actuated driving element for moving said drawer to innermost position and for holding it in such position, normally ineffective means for locking said drawer in such position arranged to be rendered effective by the operation of said first named means, and means for releasably maintaining said first named means in retracted position.

EARL M. STEVENS.
